INVENTOR.

UNITED STATES PATENT OFFICE.

GEORGE A. FREDENBURGH, OF PAWTUCKET, RHODE ISLAND.

TENSION-REGULATING DEVICE FOR THREAD-DRESSING MACHINES.

SPECIFICATION forming part of Letters Patent No. 739,663, dated September 22, 1903.

Application filed January 5, 1903. Serial No. 137,972. (No model.)

To all whom it may concern:

Be it known that I, GEORGE A. FREDENBURGH, a citizen of the United States, residing at the city of Pawtucket, in the county of Providence and State of Rhode Island, have invented a certain new and useful Improvement in Thread-Dressing Machines, of which the following is a specification.

My invention relates to a thread-tension device adapted for a thread-dressing machine which is provided with brush-cylinders and ironer-cylinders; and the object of my invention is to provide adjustable means for regulating the desired tension of the thread upon the brush and ironer cylinders of the said machine.

The invention consists in the novel construction and combination of the several parts, as hereinafter described, and specifically set forth in the claims.

In the accompanying drawings, Figure 1 represents a top plan view of my improved thread-tension device as secured in position upon a portion of the machine-frame. Fig. 2 is a cross-sectional elevation view taken in line X X of Fig. 1, illustrating the tension device as locked to the machine-frame. Fig. 3 is a similar sectional view showing the tension device as unlocked upon the machine-frame. Fig. 4 is a side sectional elevation view taken in line Y Y of Fig. 1; and Fig. 5 is a side elevation of the brush-cylinders and ironer-cylinders of a thread-dressing machine, together with their respective tension devices in position for directing the thread to said cylinders.

Similar letters of reference indicate corresponding parts in all the views.

In the drawings, A represents a cylindrical-shaped rod provided with a series of transverse grooves b b, which are divided equidistantly apart at one end of said rod, and these grooves are formed in one side of the rod and terminate with shoulders c c of the same.

d is a flanged spool or thread-roller rotatably mounted on a stud e, which is rigidly secured at the opposite end of the said rod A, and this stud projects parallel with the transverse grooves b b in the same.

B represents a bar which is made a part of the frame of the machine, and said bar extends longitudinally between the ends there-

of and is provided with a series of circular openings f f, (see Figs. 2 and 3,) divided equidistantly apart throughout the length of said bar. A screw-threaded opening g extends from the upper surface of the bar B and terminates with a smaller concentric circular opening g', which enters each of the first aforesaid openings f of the bar, as shown in Fig. 2. 60

The openings f f of the bar B are provided to receive the grooved portion of the rod A, as hereinbefore described.

C is a tube which has one end closed and its opposite end circumferentially screw-threaded to engage and rigidly secure in the threaded opening g of the bar B. 65

h is a circular plug mounted and movable in the tube C and projecting through the opening g' of the bar B, and said plug has its lower extremity provided with opposite inclined sides adapted to enter in the grooves b b of the rod A in the manner shown in Figs. 2 and 4. The upper portion of the plug h is reduced in diameter to form a shoulder, as at i, for the 70 end of a coil-spring j to bear against, and this spring is interposed between the shoulder of the plug h and the closed end of the tube C, and this construction of parts forms a locking arrangement for holding the rod A in the 75 position required upon the bar B.

Referring to Fig. 5, which shows the manner of applying my improved thread-tension device to the frame of a thread-dressing machine, the thread k in coming up from a twisting-head (not shown) passes from the rear of a thread-guide d of a tension device, as described, and which guide d directs the thread upon the brush-cylinder l, which lays the fibers of the thread, and from this cylinder l 90 the thread passes from the rear of the thread-guide d' of another tension device like that already described, and which guide d' directs the thread upon the ironer-cylinder l', which polishes the thread, and from this cylinder l' 95 the thread is directed from the rear of a thread-guide d'' of another tension device like that already explained, and this latter guide d'' directs the thread to another twisting-head above. 100

The operation of my device is as follows: When more tension of the thread k is required on the cylinders, the operator grasps the spool end portion of the rod A and gives

the same a quarter-turn toward the right in the direction indicated by the arrow in Fig. 5, and which movement will have carried the rod around from its locked position, as shown in Fig. 2, to its unlocked position, as illustrated in Fig. 3, thereby forcing upward the bottom end of the spring-compressed plug *h* from its engagement in a groove *b* of said rod, and which plug will have been brought to bear upon the smooth circular surface of the same. The operator then forces the rod inwardly on the bar *B* the distance required to give the proper tension of the thread, after which he will turn the rod back to its normal position, when the spring-controlled plug will engage in another groove of the rod, and this adjustment of the tension device carries the thread to the position as indicated by broken lines in Fig. 5. In order to prevent rotation of the plug *h* and keep its tooth-shaped end parallel with the grooves *b b* of the operating rod *A*, the said plug is provided with a pin *h'*, that is rigidly secured in its side, and this pin projects through and is guided by a vertical slot *h²*, formed in the tube *c*.

It will be understood that any number of these thread-tension devices may be mounted in the frame in accordance with the number of brush and ironer cylinders on the machine.

30 By my construction and arrangement of parts I provide a simple device that contains in itself all that is necessary to afford a quick means of adjusting the thread to the proper tension required upon the brush and ironer cylinders of a thread-dressing machine.

This invention is an improvement upon the thread-dressing machine shown and described in Letters Patent of the United States No. 702,786, issued to me June 17, 1902.

35 40 I claim as a novel and useful invention and desire to secure by Letters Patent—

1. In a thread-dressing machine having brush-cylinders and ironer-cylinders rotatably mounted on the machine-frame, the com-

bination therewith, of a bar forming a part of 45 the machine-frame, extending longitudinally thereof and provided with transverse circular openings, a circular rod provided with a series of transverse grooves on one side thereof and which grooved portion of said rod 50 loosely enters one of the openings of said bar, a thread-guide roller mounted on one end of said rod, a spring-controlled plug mounted on said bar, adapted to engage in a groove of said rod, and so arranged that a partial turn 55 of the rod, will disengage the said plug from its groove, whereby the said roller may be moved to the position required to obtain the proper tension of the thread, substantially as set forth.

2. In a thread-dressing machine provided with brush-cylinders and ironer-cylinders rotatably mounted on the machine-frame, the combination therewith, of a tension device consisting of a circular rod carrying a thread- 65 roller at one end thereof and having its opposite end portion provided with transverse grooves formed in one side of the rod, said rod having its grooved portion mounted in the machine-frame, a tube rigidly secured to 70 the machine-frame and extending vertically over said rod, a plug in said tube adapted to engage in a groove of said rod, a coil-spring interposed between said tube and said plug 75 to keep the latter in contact with said rod, and so arranged that a rotative movement of the rod will unlock its connection with the spring-pressed plug and allow the rod to be moved to the fixed position required, substantially as shown and for the purpose specified.

In testimony whereof I affix my signature in presence of two witnesses.

GEORGE A. FREDENBURGH.
